WILLIES E. MILEHAM, OF OTTUMWA, IOWA

ADJUSTABLE SHOE HEEL COVER GUARD FOR HEEL TRIMMING MACHINES

Application filed July 20, 1929. Serial No. 379,826.

This invention relates to attachments for shoe heel and sole edge trimming machines, the primary object of the invention being to provide an adjustable guard for protecting the cover leather on ladies' heels against cutting or skinning by the trimming knife which is employed for cutting down or trimming the edge of the heel top lift.

Machines at present employed for trimming the top lifts of shoe heels employ shield members which rotate with a revolving cutter which is employed for trimming the top lift of a heel. In the trimming operation the body of the heel is pressed against the shield so that the heel is subjected to a severe rubbing by the shield as it turns with the cutter. As these cutters and shields revolve at a high rate of speed, approximately six thousand revolutions per minute, it will be readily understood that the heel cover is subjected to severe treatment and often becomes damaged.

With the device embodying the present invention a stationary guard plate is employed in substitution for the rotating shield above referred to and this guard plate is eccentrically mounted with respect to the rotating trimming cutter and is also rotatably adjustable so that the amount of exposed surface of the cutting blades may be increased or decreased as desired and the shoe heel will not be subjected to a rubbing of metal thereagainst. By using the present device the edge of the top lift of the shoe heel may be trimmed flush with the edge of the heel without danger of damaging the heel covering.

Another object of the invention is to provide a shield for heel trimming machines which may be secured in a number of adjusted positions and held secure against accidental movement.

The invention will be best understood from a consideration of the following detailed description taken in connection with the accompanying drawings forming a part of the present invention with the understanding, however, that the invention is not confined to any strict conformity with the showing of the drawing but may be changed or modified so long as such changes or modi-

fications mark no material departure from the salient features of the invention as expressed in the appended claims.

In the drawings:—

Figure 1 is a view in side elevation of a portion of a shoe trimming machine showing the structure embodying the present invention applied thereto.

Figure 2 is a sectional view taken substantially upon the line 2—2 of Figure 1.

Figure 3 is a sectional view taken at right angles to the section of Figure 2.

Figure 4 is a view in front elevation of the guard plate.

Figure 5 is a view in elevation of the split collar coupling the holding yoke for the device with a shaft of the machine adjacent the heel trimmer operating shaft.

Referring more particularly to the drawings wherein like numerals of reference indicate corresponding parts throughout the several views, the numeral 1 indicates a bearing forming a part of a trimming machine, this bearing having extended therethrough a shaft 2 which carries a shoe sole trimmer, a portion of which is indicated by the numeral 3.

Arranged directly beneath the shaft 2 in the bearing 4 and parallel with the shaft, is a second shaft 5 which carries a sleeve 6 abutting at one end against the body of the machine and formed at its other end to provide a circular plate 7 against the outer face of which a rotating trimming cutter 8 works.

This cutter is mounted upon and keyed to the shaft 5, as shown in Figure 3.

The outer end of the shaft 5 is longitudinally bored and threaded, as at 9, to receive a screw 10. This screw 10 holds in position against the cutter the enlarged inner end portion 11 of a bushing 12 through which the screw passes.

The enlarged portion 11 of the bushing has a surrounding flange 13 which positions in the recess 14 formed in the back face of a guard plate 15, this recess aligning with an aperture 16 which passes through the guard plate and longitudinally through an eccentric sleeve 17 which is formed integral with the plate and projects forwardly from the outer

face thereof, as shown. The recess 14 and passage 16 are eccentric to the plate and the sleeve 17, as shown in Figure 4. The bushing 12 passes through the passage 16 of the sleeve and, as shown in Figure 3, the bushing is of slightly greater length than the passage through the sleeve so that when the screw 10 is drawn in tightly to hold the bushing securely against the face of the cutter 8, the sleeve and shield 15 will not be held tightly but will be permitted to rotate about the bushing.

Surrounding and secured to the shaft 2 directly above the guard plate 15 and sleeve 17 is a collar 18 having formed circumferentially thereabout a recess 19 in which positions a two part ring 20, one of the parts of which is supplied with a grease cup 21.

Each of the parts of the ring 20 has formed in the outer face thereof midway between its ends, a pivot pin recess 22 designed to receive the reduced tip 23 of a screw member 24. Each of these screws 24 is adapted to have threaded engagement in a recess formed in the end of a yoke 25 which yoke is designed to receive the two part ring 20 in the manner shown in Figure 2, so that the apertured ends thereof will be at diametrically opposite points upon this ring and the tips of the screws 23 will be in position to engage in the apertures 22, as shown.

Suitable holding nuts 26 are threaded onto screws 23 to hold the same in position. Extending downwardly from the yoke 25 intermediate its ends is a sleeve 27 which is designed to receive a rod 28 which is reduced at its lower end as indicated at 29.

Surrounding the sleeve 17 is a strap 30 which has formed integral therewith an internally threaded sleeve 31 which is adapted to receive the threaded reduced portion 29 of the rod 28.

By referring to Figure 3 it will be seen that the eccentric is illustrated as being at its lowest point so that the guard 15 leaves exposed only a small portion of the cutter and when the eccentric is in this position the rod 28 is backed out of the sleeve 31 until the upper end abuts the bottom of the socket 27 in which it is positioned. Thus it will be seen that no movement of the eccentric or of the guard disk can occur as a result of frictional engagement between the rotating cutter and the portion 11 of the bushing.

When the guard disk is to be shifted so as to expose more of the cutter for use the post 28 may be rotated to thread its lower end into the sleeve 31 whereupon the disk 15 may be rotated until the desired amount of the cutter is uncovered. The rod 28 is then reversely rotated so as to be backed out of the sleeve 31 until its upper end is brought into abutting engagement with the inner end of the socket 27. Since the cutter rotates in a clockwise direction the tendency possibly would

be, if the upper end of the rod 28 was not already in the socket 27 as far as it can go, for the frictional contact between the cutter 8 and the portion 11 of the bushing to cause the guard plate 15 to rotate but this cannot occur for the reason that the rod 28 as previously stated is backed out of the sleeve 31 after the proper setting of the plate is made. Therefore, the rotating of the cutter will only act through its frictional engagement with the bushing to maintain the guard disk in the set position. There is thus provided a guard against which a shoe heel may be pressed while trimming the top lift thereof and a means for gauging an amount of cutter exposed so that the lift of the heel may be cut down flush with the edge of the heel without in any way damaging the heel covering.

Having thus described my invention, what I claim is:—

1. In a trimming machine having a rotary cutter, a guard plate overlying one face of the cutter and rotatably supported, eccentric means for moving the edge of the guard plate when rotated relative to the edge of the cutter, and means for adjustably holding the plate in position, comprising an eccentric strap, a bar member adjustably secured to the strap, and means for securing the bar member to a fixed part of the machine.

2. In a trimming machine of the character described employing a rotary cutter, a bushing mounted against and projecting from the face of the cutter, a guard disk, an eccentric body projecting from one face of the guard disk, said bushing passing through the disk and eccentric body, means for maintaining the disk and body in position upon the bushing, a strap about the eccentric body, and means carried by said eccentric strap and adjustably connected to a fixed body for holding the strap against movement.

3. In a trimming machine of the character described employing a rotary cutter, a bushing mounted against and projecting from the face of the cutter, a guard disk, an eccentric body projecting from one face of the guard disk, said bushing passing through the disk and eccentric body, means for maintaining the disk and body in position upon the bushing, a strap about the eccentric body, a rod adjustably attached at one end to the strap, and means for receiving and holding the other end of said rod to secure the same and said strap against movement.

4. In a trimming machine of the character described, having a pair of shafts one thereof carrying a rotary cutter, a guard disk eccentrically mounted before the face of and relative to the cutter, an eccentric body carried by the guard disk, means for supporting the guard disk and maintaining the same against rotation with the cutter, a strap about the eccentric, a holding rod adjustably attached

at one end to the strap, a collar carried by the other shaft, a yoke loosely held by said collar, and means forming a part of the yoke for loosely receiving the other end of the 5 rod.

5. In a trimming machine of the character described having a shaft carrying a rotary cutter at its end, a guard disk positioned before the front face of the cutter and eccentric thereto, a member extending longitudinally from the end of the shaft through and rotatably supporting said disk, said disk when rotated having its periphery shifted relative to the periphery of the cutter, a 10 threaded sleeve having pivotal connection with and extending radially from said disk, and a holding bar having one end threadably engaged in said sleeve and having its other end connected to an adjacent fixed portion 15 of the machine.

6. In a trimming machine of the character described having a rotating shaft provided with a threaded bore opening through one end and a cutter mounted on said end, a pin 20 having one end threaded into said bore, a bushing mounted on said pin and having a disk body formed at its inner end abutting the adjacent face of said cutter, a guard disk 25 having an eccentric body projecting from one face, said disk and body having a passage formed eccentrically therethrough for the reception of said bushing, the guard disk abutting the disk of the bushing, an eccentric strap surrounding said eccentric body, and 30 means for connecting said strap with an adjacent fixed portion of the machine for maintaining the eccentric body in a set position.

7. In a trimming machine of the character described having a rotating shaft provided 40 with a threaded bore opening through one end and a cutter mounted on said end, a pin having one end threaded into said bore, a bushing mounted on said pin and having a disk body formed at its inner end abutting 45 the adjacent face of said cutter, a guard disk having an eccentric body projecting from one face, said disk and body having a passage formed eccentrically therethrough for the reception of said bushing, the guard disk abutting the disk of the bushing, an eccentric strap surrounding said eccentric body, an interiorly threaded sleeve formed integral with 50 said strap, a bar member having one end threadably engaged in said sleeve, and means 55 for connecting the other end of said bar with an adjacent fixed part of the machine.

In testimony whereof I hereunto affix my signature.

WILLIES E. MILEHAM.
